HYPODERMIC SYRINGE

Original Filed May 18, 1925

Inventor
ARTHUR E. SMITH,

By *Shepherd Campbell*
Attorney

UNITED STATES PATENT OFFICE

ARTHUR ERVIN SMITH, OF LOS ANGELES, CALIFORNIA

HYPODERMIC SYRINGE

Application filed May 18, 1925, Serial No. 31,030. Renewed September 23, 1926.

This invention relates to hypodermic syringes and it has for its object to provide a device of this character into which a medical package of the nature of an ampule may be charged, after the manner of loading a gun, the several parts being so correlated and arranged that a freshly made medicinal preparation may be quickly prepared and injected by the syringe without ever coming into contact with human hands, unsterilized receptacles or with the atmosphere.

It is a further object of the invention to provide a syringe of the character indicated adapted to form the necessary fluid tight joint between the ampules and the syringe, with facility and dispatch and with very little trouble upon the part of the user.

Further objects of the invention and refinements of construction will be pointed out in the detailed description which follows:

In the accompanying drawings:

Figure 1 is an enlarged vertical sectional view of a syringe constructed in accordance with the invention.

Figure 2 is a side elevation of the syringe upon a smaller scale.

Figure 3 is a magnified sectional view of the lower portion of the syringe, illustrating an elastic packing cone, and a discharge tube hereinafter described.

Figure 4 is a transverse sectional view upon line 4—4 of Figure 2.

Figure 5 is a plan view of the structure illustrated in Figure 3, upon a smaller scale, and

Figure 6 is a side view of the ampule, hereinafter described.

Like numerals designate corresponding parts in all of the figures of the drawings.

The syringe of the present invention is particularly designed to discharge the contents of the ampule shown in Figure 6. This ampule comprises a glass body 5, having a tapered front end 6, which terminates in a breakable tip 7. This tip is rendered readily separable from the remainder of the ampule by scoring, notching, etching, or otherwise weakening it as indicated at 8. The ampule contains a rubber or other stopper 9 which is adapted to act as a piston to expel the con-

tents of the ampule through the open tapered end 6 of the ampule after it has been broken therefrom, as hereinafter described. I preferably close the rear end of the ampule indicated at 10 and weaken it by a scored or cut line, at 11, so that this rear end may be readily broken therefrom. Thus this closed rear end protects the stopper and maintains the whole in absolutely sterile condition until the time of use arrives.

Certain medicinal compounds, and particularly certain anesthetics, are unstable in solution and this disintegration or chemical change may produce deleterious effects upon the patient if such a solution was injected.

Such medicinal compounds should be freshly prepared at the time of use. In the present case the constituent elements of the medicinal preparation in the ampules are maintained separate from the vehicle until the time of use arrives.

For example the body of liquid indicated at 12, in the ampule, may be distilled water, and an anesthetic or other medicinal preparation in the form of tablets or powder may be contained within a paraffin or other waterproof capsule 14, which is fusible or meltable under a comparatively low degree of heat.

Thus when the time of use arrives, by placing the ampule into warm water and increasing the temperature or holding it under running hot water, the low fusible wall may be melted and the medicinal ingredients permitted to mix with the distilled water or other vehicle.

By holding the ampule in a vertical position with its large end upward, the released paraffin may be caused to travel upward and find a seating in the concave face 9a of the stopper 9, so that it will thereafter constitute, in effect

a part of the piston in ejecting the medicinal preparation through the open end of the ampule. When the paraffin rises it is still hot and in molten condition. After it has entered and seated itself in the concave face of the stopper, it is congealed and hardened, in contact therewith, by placing the ampule in cold water or holding it with large end upward under running cold water.

The syringe comprises a barrel 15, having a cross bar 16 for engagement by the fingers

of the operator, the palm of whose hand engages a handle or cross bar 17 upon the upper end of a plunger rod 18. This plunger rod carries a plunger 19 at its inner end which 5 is adapted to engage the stopper 9 and force said stopper downwardly to expel the liquid 12 from the ampule. The plunger rod 18 passes through a plurality of telescopic tubular members 20, 21 and 22 which may be multiplied in number to any desired extent. A 10 spring 23 located within these tubular members bears between a cap 24 and a head 25, of the innermost telescopic member 22. The cap 24 is adapted to be engaged with the upper 15 end of the barrel 15 through a medium of a bayonet joint connection, of a usual and well known type, indicated at 25'. The lower end of the barrel 15 is internally threaded to receive a cap 26, which terminates in a tapered tip adapted to receive a correspondingly tapered sleeve 28 of the hub 29 of a hypodermic needle 30. The cap 26 is internally formed with a conical recess 31 which receives a correspondingly shaped rubber, or other 20 compressible packing cone 32. The lower end of the barrel 15 is provided with a ring 33 having a beveled lower face 34 which is adapted to engage the upper and convex surface of the cone 32 when the cap 26 is screwed into place, to thereby compress the cone 32 inwardly. The cone 32 is provided with a conical recess 35, which receives the tapered lower end of the ampule when the tip 7 is removed therefrom. The tapering shape of the 25 lower end of the ampule causes it to have wedging engagement in the conical recess 35 and to tend to compress the material of the cone outwardly. Thus this inward and outward compression of the cone results in establishing a fluid tight joint between the ampule and the cone upon the one hand and between the cone and the ring 33 upon the other hand. The disposition of the ring 33 is in such position that its contact with the cone 32 in the 30 manner illustrated insures that the ampule will not be forced downwardly far enough for it to be ruptured by contact with the ring 33. A discharge tube 37 is soldered into engagement with the tip and its lower end 35 opens into the needle 30. However, its upper end is preferably closed as indicated at 38 in Figure 3. It will be noted that the discharge tube projects upwardly into conical recess 35 so that its upper portion lies free of contact with the cone 32. This permits the liquid of the ampule to find access to the interior of the discharge tube 37 by passing through lateral openings 39 formed in the discharge tube adjacent the upper ends thereof. The reason 40 for arranging the parts in this relation is to prevent any possibility that the paraffin or other low fusible material released when the ampule is heated, will close the discharge tube upon the final inward movement of the 45 plunger.

In use the ampule is charged into barrel 15, after the plunger and associated parts have been removed by the release of the bayonet connection between the cap 24 and barrel 15, and after the rear portion 10 of the ampule 70 has been removed by breaking it off along the line 11, and after breaking the ampule tip 7 at 8. Then when the plunger is restored and the bayonet connections are engaged, the head 25 bears with yielding tension upon the rear edge 40 of the ampule and forces the tapered lower end of the ampule into the conical recess 35 of the cone 32.

Then when the plunger rod and plunger 18 are thrust downwardly, the plunger 19 engages the stopper 9 and forces said stopper into the ampule after the manner of a piston. This pressure upon the liquid in turn tends to force the ampule downwardly and increases the pressure upon the packing cone 85 and associated parts, expelling the liquid from the interior of the ampule through the openings 39, discharge tube 37 and needle 30 in a manner, which will be readily understood.

Since the head 25 is rendered yielding by reason of its telescopic mounting and the presence of the spring 23 it follows that it may be positioned at varying points in the length of the barrel and still exercise its 95 function. By virtue of this arrangement, the one syringe is adapted to handle ampules of varying lengths and consequently of varying cubic capacities. Thus ampules ranging from one cubic centimeter to four cubic centimeters, or any fraction thereof, may be efficiently handled in the one syringe. This is not possible with any device of this character of which I have knowledge.

While I prefer to use the discharge tube 105 with the openings laterally disposed below the upper end thereof and with the upper end closed, this is not essential in the case of ampules which do not utilize paraffin or the like. Thus it is to be understood that 110 the invention includes the use of a discharge tube having an open top.

I preferably leave the sides of the barrel 15 open as indicated at 15a to constitute a sight opening through which the contents of 115 the ampule will be visible and so that the movement of the cork 9 and the extent to which the contents of the ampule have been discharged, may be readily observed by the surgeon or dentist.

Furthermore this renders it possible for the operator to see the conical opening 35 in the upper end of the cone 32 and aids in positioning the broken off lower end of the ampule.

When the piston constituted by the stopper and the paraffin, starts to move downwardly, the pressure forces the paraffin into the concave face of the cork and causes lateral expansion of the relatively thin edges of the 130

cork against the wall of the ampule, thus making an absolutely nonleakable joint between the piston and the ampule. At the same time the pressure applied in the explosion of the medicinal solution, tends to force the ampule toward the rubber cone and this in turn forces the small end of the ampule into the cone shaped depression of the rubber cone, making a nonleakable joint between the outer 5 part of the glass tip and the said cone. Furthermore, the pressure forces the rubber cone itself into its tapered socket, thereby compressing the rubber cone against the needle or tube, thus making a nonleakable joint between the tube and the rubber cone.

It is to be understood that the invention is not limited to the precise construction set forth but that it includes within its purview whatever changes fairly come within either 10 the terms or the spirit of the appended claim.

Having described my invention, what I claim is:

A syringe of the character described comprising a barrel, having a sight opening 25 formed therein, a cap adapted to be screwed into the lower end thereof, said cap having a tapering recess formed therein, a conical rubber packing element seated in said recess, a discharge tube extending through said 30 packing element and permanently united with the cap and having a closed upper end with lateral openings therebelow, said packing element having a conical recess formed in its upper face adapted to receive the 35 broken off nose of an ampule, a plunger rod, a spring surrounding said plunger rod, a handle for operating the plunger rod, a removable cap on the barrel, a plurality of telescopic elements surrounding the plunger 40 rod, said spring bearing between said cap and the lowermost of said telescopic elements and a head carried by the lowermost telescopic elements adapted to engage the rear end of an ampule to force its nose into 45 engagement with the tapered recess of the rubber packing element.

In testimony whereof I hereunto affix my signature.

ARTHUR ERVIN SMITH.
